US00D957424S

(12) **United States Design Patent** (10) Patent No.: **US D957,424 S**
(45) Date of Patent: **** Jul. 12, 2022**

(54) **DISPLAY SCREEN OR PORTION THEREOF WITH GRAPHICAL USER INTERFACE**

- (71) Applicant: **Apple Inc.**, Cupertino, CA (US)
- (72) Inventors: **Christopher Foss**, San Francisco, CA (US); **Jonathan P. Ive**, San Francisco, CA (US); **Chanaka Karunamuni**, San Jose, CA (US); **Matthew Dean Rohrbach**, San Francisco, CA (US); **Alessandro Francesco Sabatelli**, San Francisco, CA (US)
- (73) Assignee: **Apple Inc.**, Cupertino, CA (US)

(**) Term: **15 Years**

(21) Appl. No.: **29/807,555**

(22) Filed: **Sep. 13, 2021**

Related U.S. Application Data

(63) Continuation of application No. 29/695,182, filed on Jun. 17, 2019, now Pat. No. Des. 930,662, which is a continuation of application No. 29/660,295, filed on Aug. 20, 2018, now Pat. No. Des. 851,676, which is a continuation of application No. 29/600,156, filed on Apr. 10, 2017, now Pat. No. Des. 826,241, which is a continuation of application No. 29/558,856, filed on Mar. 22, 2016, now Pat. No. Des. 783,639, which is a continuation of application No. 29/540,700, filed on Sep. 26, 2015, now Pat. No. Des. 767,632, which is a continuation of application No. 29/457,372, filed on Jun. 10, 2013, now Pat. No. Des. 742,894.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
